Patented Sept. 29, 1925.

UNITED STATES PATENT OFFICE.

ROCCO PRONINI, OF SMITH RIVER, CALIFORNIA.

RAIL FASTENER.

Application filed January 5, 1925. Serial No. 666.

To all whom it may concern:

Be it known that I, Rocco PRONINI, a citizen of the United States, residing at Smith River, in the county of Del Norte and

5 State of California, have invented certain new and useful Improvements in a Rail Fastener, of which the following is a specification.

The present invention relates to improvements in devices for securing rail road rails to ties or sleepers, and the primary object of the invention is to provide devices of this character whereby the rail may be rigidly secured to the tie in an effective manner for preventing lateral or longitudinal creeping of the rail.

A further object of the invention is to provide an improved rail fastener embodying movable means which are adapted to be moved into engagement with the base flanges of the rail, and there locked against movement laterally from the rail.

A still further object of the invention is to provide an efficient rail fastening device whereby when the device is in assembled operative relation to the rail, the spikes employed for retaining the tie plate upon the tie, will be held against withdrawal from the tie.

30 Other objects and advantages of the invention will be apparent during the course of the following detailed description, taken in connection with the accompanying drawings, forming a part of this specification, and in which drawings:

Figure 1 is a plan view showing a preferred embodiment of the invention, and showing the device in assembled operative relation to a portion of a rail;

40 Figure 2 is a section view taken on line 2-2 of Figure 1, looking in the direction of the arrows;

Figure 3 is a sectional view taken substantially on line 3-3 of Figure 1, looking in the direction of the arrows;

Figure 4 is a top plan view of a tie plate as used in the form of invention shown in Figure 1;

50 Figures 5 and 6 are top and bottom plan views, respectively, of the form of retaining blocks as shown in Figure 1;

Figure 7 is a perspective view of a key used for locking the retaining blocks in operative relation to a rail;

55 Figure 8 is a vertical cross section view

showing a slightly modified form of retaining block applied to one side of a rail;

Figure 9 is a plan view showing a slightly modified form of the device when used in conjunction with a guard rail;

Figure 10 is a sectional view taken on line 10-10 of Figure 9, looking in the direction of the arrows;

Figure 11 is a top plan view of a two rail tie plate as used in the form of invention as shown in Figure 9;

Figure 12 is a bottom plan view of a spacing clamp as used in connection with a main and guard rail as illustrated in Figure 9 of the drawings; and,

Figure 13 is a bottom plan view of a retaining clamp as used in the form of invention shown in Figure 9 of the drawings.

Referring to the drawings in detail, and wherein similar reference characters designate corresponding parts throughout the several views, the letter A may generally designate a main rail of usual construction; B an underlying sleeper or cross tie for supporting the rail A; and C the improved rail fastener adapted for rigidly securing the rail A upon the cross tie B. The fastener C comprises a chair or tie plate D which is adapted to be disposed beneath the base of the rail A and rest upon the cross tie B; retaining blocks E for sliding movement into and out of operative relation with the rail A; and means F for locking the retaining blocks E in operative relation with the rail A.

Referring first to the tie plate D as is employed in connection with the form of the device as illustrated in Figures 1 to 8 of the drawings, and which form is for the purpose of securing a single rail to its cross tie; the plate is substantially rectangular shaped in plan, and has provided at each end of its upper face in longitudinal offset

relation, longitudinally extending guideways or dovetailed recesses 10. Extending longitudinally from the inner end of each recess 10, and at a point centrally of the recesses, are supporting or gauge blocks 11;

100 and at the outer ends of which, apertures 12 are provided through which the fastening spikes 13 may pass. Extending through the plate D at opposite sides of the major axis of each recess 10, and at a point substantially midway of the recesses, are transversely aligned keyways 14 formed at the upper

portion of the plate with elongated slots 15 having enlarged central portions, and beneath which slots enlarged pockets 16 of annular formation are formed for presenting 5 a shoulder beneath the slots 15. A depending flange 17 is provided along one longitudinal edge of the tie plate for aiding in preventing creeping of the plate transversally of its supporting tie.

10 Referring now to the retaining blocks E which are of like construction, each is formed with a base plate 18 having a rail engaging boss 19 formed on the upper face thereof and projecting from one longitudinal edge of the plate at a point midway the length thereof. Formed directly beneath the boss 19, and projecting in a like manner as the boss, is a dovetailed tenon 20 having a slot 21 provided in its forward 20 end; and which slot extends upward for a short distance into the lower portion of the boss 19 in a manner so that when the block is slid laterally toward the rail with the tenon 20 fitting in the recess 10, the upwardly and outwardly inclined top wall of the slot 21 will engage the head of the spike 13 for forcing the spike into firm contact with the base flange and also prevent the spike from moving upwardly. When moved 30 into this position, the forward end of the tenon 20 will straddle the shank of the spike with the divided portions 20' of the tenon lying at each side of the supporting block 11 and underlying a portion of the base flange 35 of the rail for holding the rail engaging boss 19 in contact with the upper portion of the base flange of the rail. Extending through the base plate 18 at each side of the boss 19, and adjacent the inner edge of the plate, are 40 slots 22 conforming to the shape of the slots 15 forming a part of the keyways 14 provided in the tie plate D. Provided adjacent each of the slots 22, and extending through the plate 18, are apertures 23 which 45 preferably flare outwardly at their lower portions, and the object of these apertures will be subsequently set forth.

With reference to Figure 8, the retaining block E' is provided with an enlarged rail 50 engaging boss 19' for engaging the web of the rail and the under portion of one side of the upper flange of the rail. This form of retaining block is especially well adapted for use at curves where a greater tilting 55 strain is placed upon the rails.

The means F for locking the retaining blocks E in operative relation with the rail A, consists of a key formed with a head 24 having a laterally extending arm 25, a shank 26 depending from the head, and having provided at the lower end of the shank, lugs or wings 27. An aperture 28 is provided in the free end of the arm 25 for permitting passage of a retaining pin 29 65 for retaining the key in a locked position.

In practice, the rail A is placed on the tie plate D with the longitudinal edges of the base flange aligned with the outer ends of the supporting blocks 11. The spikes 13 may then be driven through the apertures 12 for retaining the rail in position upon the tie plate, and rigidly securing the tie plate to the cross tie B. The retaining blocks E may then be slid laterally toward the rail with the dovetailed tenons 20 moving in the dovetailed recesses 10, until the slots 22 of the blocks align with the similarly extending slots 15 of the keyways 14, and in which position the divided portions 20' of the tenon will lie in surface contact with the lower face of the rail base, and the boss 19 will lie in surface contact with the upper face of the rail base for firmly retaining the rail in a non-tilting position upon the tie plate D. The shanks of the keys F may then be inserted in the aligned slots 15 and 22 by alignment of the wings with the slots, and when fully inserted, given a quarter turn or turned until the aperture 28 aligns with the aperture 23, and in which position the wings 27 will lie beneath the shoulder formed in the keyway thus locking the retaining blocks in operative relation to the rail. The retaining pin 29 may now be inserted in the aligned apertures 23 and 28, and by striking the head of the pin, the lower end of the shank portion, by reason of its abutting relation with the metal tie plate D, will be caused to expand into the enlarged lower portion of the aperture 23 for preventing easy or accidental withdrawal of the pin.

Referring now to the slightly modified form of the invention as shown in Figures 9 to 13 inclusive, and which shows the device as used for fastening a main and a guard rail in parallel spaced relation; the tie plate D' has provided in merely one end thereof a longitudinally extending dovetailed recess 30 which is identical in formation to the recesses shown in Figures 1 to 8 inclusive, and is also provided with similarly formed keyways 31 for receiving the keys F for retaining the block E in adjusted relation at the outer side of the main rail A. This plate D' has in addition to the recess 30, an intermediate keyway 32 disposed between the seats of the main rail A and guard rail A', and an inner keyway 33 disposed inwardly of the seat of the guard rail. These keyways 32 and 33 are formed similar to the keyways 14, and have the slots which are provided at the upper portions thereof, extending in planes parallel to the rails. Apertures 34 are also provided in the plate in transverse alignment with each of the keyways 32 and 33.

A spacing clamp 35 for positioning between the main and guard rails, consists of a double bossed head 36 having a laterally extending arm 37 provided at its free end 130

with an aperture 38, and depending from the head, is a shank portion 39 having wings 40 formed at its free end.

5 A retaining clamp 41 for positioning at the inner side of the guard rail A', consists of a head 42 having a laterally extending arm 43 provided at its free end with an aperture 44, and depending from the head, is a shank portion 45 having wings 46 formed at its free end.

10 In practice when the device is employed for fastening a main and a guard rail in parallel spaced relation, the spacing clamp 35 may first be locked in an operative position in the keyway 32 by a retaining pin 47.

15 The main rail A may then be slid into position beneath one boss of the spacing clamp, and the retaining block E slid into operative relation as in the form shown in Figures 20 1-8 inclusive. The retaining clamp 41 may then be inserted in the keyway 33 and swung into operative locked relation with the inner flange of the guard rail, and locked in this position by a retaining pin 48.

25 From the foregoing description of this invention it will be apparent that a novel and efficient rail fastening device has been provided wherein the rail engaging elements of the device will be locked in operative relation to the rail in a manner as to eliminate 30 all possibility of their working loose due to vibration or other causes.

35 Various changes may be made as to the shape, size and arrangement of parts herein shown and described, without departing from the spirit of the invention or the scope of the claims.

I claim:—

1. A rail fastener comprising a tie plate 40 having guideways provided in its upper face, and keyways in said plate; retaining blocks slideable in said guideways, having rail engaging portions for engaging the upper portion of the base flange of the rail, and being provided with slots for alignment with said keyways; means for securing the tie plate upon its supporting tie; and rotatable locking means adapted to extend through the aligned keyways and slots 45 for locking the retaining blocks in operative relation to the rail.

2. In a rail fastener, the combination of a tie plate having a guideway provided in its upper face, and a keyway in said plate; a retaining block slideable in said guideway, having a rail engaging portion for engagement with the base flange of the rail, and being provided with a slot for alignment with said keyway; means for securing the tie plate upon its supporting tie; and locking means extending through the aligned keyway and slot, and lying wholly above the lower surface of the tie plate, for locking the retaining blocks in operative relation to 60 the rail.

3. In a rail fastener, the combination of a tie plate having a dovetailed recess provided at one end of its upper face and extending in a lateral direction with respect to the rail, and a keyway in said plate; a retaining block provided with a dovetailed tenon for sliding movement in the dovetailed recess, a rail engaging portion, and a slot for alignment with said keyway; means for securing the tie plate upon its supporting tie; and rotatable locking means extending through the aligned slot and keyway for preventing lateral movement of the retaining block with respect to the rail.

4. In a rail fastener, the combination of a tie plate having a recess provided at one end of its upper face and extending in a lateral direction with respect to the rail, and having keyways disposed at opposite sides of the recess; a retaining block slideable in said recess having a rail engaging boss formed on the upper face thereof, and being provided at opposite sides of the boss with slots for alignment with said keyways; and locking means extending through the aligned slots and keyways for locking the retaining blocks in operative relation to the rail.

5. In a rail fastener, the combination of a tie plate having a recess provided at one end of its upper face and extending in a lateral direction with respect to the rail, and having keyways disposed at opposite sides of the recess; a retaining block slideable in said recess having a rail engaging boss formed on the upper face thereof, and being provided at opposite sides of the boss with slots for alignment with said keyways; rotatable keys extending through the aligned slots and keyways for holding said retaining blocks in operative relation to the rail; and means for retaining said rotatable keys in a locked condition.

6. In a rail fastener, the combination of a tie plate having a guideway provided at one end of its upper face, and a keyway formed at its upper portion with an elongated slot providing a shoulder in the keyway; a retaining block slideable in said guideway, having a rail engaging portion, and a slot conforming in shape to the slot in said tie plate; a rotatable key extending through the slot in the retaining block and into said keyway, and being provided with wings for engaging beneath the shoulder when the key is rotated; and means for retaining the rotatable key in a locked operative position.

7. In a rail fastener, the combination of a tie plate having a guideway provided in its upper face, and a keyway formed with a shoulder; a retaining block slideable in said guideway for engaging the base flange of the rail, having a slot for alignment with said keyway and an aperture having an outwardly flaring lower portion; a rotatable

- key having an arm provided with an aperture, and having a shank portion extending through the aligned slot and keyway provided with wings for locking engagement beneath the shoulder in said keyway upon rotation of the key; and a retaining pin extending through the aligned apertures in the key arm and retaining block with its shank portion in abutting relation with the upper face of the tie plate, whereby upon striking the head of the pin, the lower portion of the shank will be caused to expand into the enlarged lower portion of the aperture in the retaining block.
15. 8. In a rail fastener, the combination of a tie plate having a guideway provided at one end of its upper face and extending in a lateral direction with respect to the rail, and having an aperture in said guideway; a spike passing through the aperture in said guideway and engaging the upper portion of the base flange of the rail; a retaining block slidable in said guideway, having a rail engaging boss overlying said spike and provided in its forward end with a slot having an upwardly and outwardly inclined top wall for engaging the head of the spike; and means for locking the retaining block in operative engagement with the rail.
30. 9. In a rail fastener, the combination of a tie plate having a guideway provided at one end of its upper face and extending in a lateral direction with respect to the rail, and having an aperture in said guideway; a spike passing through the aperture in said guideway and engaging the upper portion of the base flange of the rail; a retaining block slidable in said guideway, having a boss for engaging the upper portion of the rail base in overlying relation to the spike and a tenon having a divided portion straddling the spike and engaging the under portion of the rail base, the divided portion of the tenon forming a slot having an upwardly and outwardly inclined top wall adapted to engage the head of the spike for forcing the head into tight engagement with the base flange; and means for locking the retaining block in operative engagement with the rail.
55. 10. A rail fastener comprising a tie plate having guideways provided at each end of its upper face in offset relation and extending in a lateral direction with respect to the rail, and keyways disposed at opposite sides of the guideways; spikes extending through apertures in said guideways and engaging the base flange of the rail for securing the rail to the tie plate, and the tie plate upon its supporting tie; retaining blocks slidable in said guideways for engaging the base flange at opposite sides of the rail, and being provided with slots for aligning with the keyways in said tie plate; and locking means extending through the aligned slots and keyways for retaining the blocks in operative relation to the rail.
11. A rail fastener comprising a tie plate having dovetailed recesses provided at each end of its upper face and extending in a lateral direction with respect to the rail, and keyways disposed at opposite sides of the recesses; spikes extending through apertures in said guideways and engaging the base flange of the rail for securing the rail to the tie plate, and the tie plate upon its supporting tie; retaining blocks formed with a base plate having a dovetailed tenon formed on its lower face and a rail engaging boss formed on its upper face in overlying relation to the tenon, and having slots provided in the base plate at opposite sides of the boss aligning with the keyways in said tie plate; and rotatable locking keys extending through the aligned slots and keyways for locking the blocks in operative relation at opposite sides of the rail.
12. In a rail fastener for a main and a guard rail, the combination of a tie plate having keyways formed therein at each side of the seating surface of the main and the guard rail; rail engaging members having key portions adapted to extend into said keyways for locking engagement therein upon rotation of the key portions; and means for retaining the key portions in a locked condition.
13. A rail fastener for main and guard rails, comprising a tie plate having a guideway provided in one end thereof adjacent the seat of the main rail, and having keyways provided at each side of the guideway, an intermediate keyway between the seats of the main and guard rail, and a keyway inwardly of the seat of the guard rail; a retaining block slidable in the guideway and engaging the outer portion of the base flange of the main rail; means for locking the block in operative relation to the rail; a spacing clamp adapted for rotary movement into locking relation in said intermediate keyway and having a double bossed head for engaging the adjacent portions of the base flanges of the main and guard rails; a retaining clamp adapted for rotary movement into locking relation in said inner keyway, and having a bossed head for engaging the inner portion of the base flange of the guard rail; and means for securing the tie plate upon its supporting tie.

ROCCO PRONINI.
